12 Claims. (Cl. 263—6)

2

Fig. 3A is a similar view in continuation of Fig. 3 showing a part of the furnace intermediate the ends.

Fig. 4 is a similar view in continuation of Fig. 3A showing the entrance end of the furnace.

5 Fig. 5 is a transverse sectional view on line 5—5 of Fig. 3A.

Fig. 6 is a fragmentary transverse sectional view of a modification.

Fig. 7 is an enlarged vertical sectional view of one 10 of the refractory rings making up the conveyor roll shown in Fig. 2.

Fig. 8 is an end elevation of said ring.

The assembled furnace or kiln shown in Fig. 1 comprises a discharge end section indicated as a whole at 10,

15 an entrance end section indicated at 11, and three identical intermediate sections indicated at 12. All of these sections are preferably the same length which may be three feet, and they are all prefabricated tubular sections consisting of a steel framework lined with insulating 20 refractory brickwork. The sections are adapted readily to be connected end-to-end, so that a furnace-kiln of any desired length can quickly be constructed and disassembled for changing the overall length or for transportation to another location.

25 The intermediate sections or units 12 will be described first because the end sections are the same basically plus a few additional features. Referring first to Figs. 3A and 5, each tubular section 12 is rectangular in plan and transverse section, and has four steel angles 13 extending vertically along its four-vertical corners, one leg of each angle abutting the side of the section and the other leg being outturned to provide an attaching flange to attach to a similar angle flange on the adjoining section. The flanges of adjoining angles 13 are detachably connected 30 by bolts 14. The bottom ends of angles 13 have horizontal flanges or floor plates 15.

35 The angles 13 may be connected near their top ends by horizontal angles 16 and near their bottom ends by horizontal angles 17. Adjacent to the angles 17, opposite angles 13 are connected by transverse horizontal angles 18 supporting a horizontal steel bottom plate 19 on which the brickwork lining of the section is supported. The flanges of abutting angles 13 of adjoining sections are detachably connected by bolts 20. Between the horizontal 40 angles 16 and 17 are horizontal angles 21 for supporting the bearings 22 for the roll shafts 23, and horizontal reinforcing channels 24 may connect the corner angles 13 at points spaced above the roll bearings. The top ends of opposite angles 13 are preferably connected by tie 45 bolts 25.

50 The refractory sidewalls lining the framework are indicated generally at 27, and mainly constitute insulating refractory brick capable of withstanding high temperatures and laid up with insulating cement. The roll mounting blocks 28 and 29 are preferably of fire clay and accurately located to properly position the roll shafts 23. Above the roll blocks are two vertically spaced ledges 30 and 31 for supporting upper muffle plates, and these ledges are preferably formed by courses of firebrick to 55 reduce breakage. Below the roll blocks are similar vertically spaced ledges 32 and 33 for supporting lower muffle plates.

55 A central longitudinal supporting wall 34 of open construction is preferably of firebrick and the furnace bottom 35 between the side walls 27 and central wall 34 may consist of insulating refractory castable material supported on the bottom plate 19. The top of the furnace is closed 60 between the side walls by a roof block assembly of insulating refractory blocks 36 held together by tie bolts 37 connected at their ends to angles 38 resting on the tops of the side walls. This roof assembly can be re-

The invention relates generally to continuous furnaces and kilns for heating, firing and heat treating various products and materials. More particularly, the invention relates to an improved sectional furnace or kiln adapted for treating various glass and ceramic products over a wide range of temperatures and with controlled atmospheres.

Conventional furnaces and kilns for continuously heating and treating glass and ceramic products are massive and are expensively constructed in place to suit particular products and other specific requirements; e. g. high or low temperatures, muffle firing or direct firing, ordinary atmospheres or controlled atmospheres, etc.

It is an object of the present invention to provide an improved furnace-kiln made up of prefabricated sections which are easily assembled to provide any desired length of furnace, and which are easily disassembled to change the overall length as desired.

Another object is to provide an improved sectional furnace-kiln which is adapted to be used over a wide range of temperatures for treating a variety of products.

A further object is to provide an improved sectional furnace-kiln which is easily adaptable for direct or indirect firing.

Another and more specific object is to provide an improved sectional furnace-kiln having sectional and removable muffle plates.

A still further object is to provide an improved sectional furnace-kiln having a novel conveyor roll construction.

Still another object is to provide an improved furnace-kiln having upper and lower muffle plates closely adjacent to the conveyor hearth, and means for recirculating the furnace atmosphere through the muffle chamber below the lower muffle plates to increase thermal efficiency by convection heating.

These and other objects are accomplished by the improved furnace-kiln comprising the present invention, a preferred embodiment of which is shown by way of example in the accompanying drawings and described in detail herein. Various modifications and changes in details of construction are comprehended within the scope of the invention defined in the appended claims.

The present improved furnace-kiln is particularly adapted for enameling and refractory coating metals and heat treating such products; for annealing, decorating and forming glass products; and for firing, decorating and treating various ceramic products.

Referring to the drawings:

Fig. 1 is a side elevation of a continuous furnace or kiln according to the invention having five prefabricated sections, comprising two end sections and three intermediate sections, connected together in end-to-end relation.

Fig. 2 is a detached elevational view, partly in section, of one of the improved conveyor rolls journaled in the sections.

Fig. 3 is an enlarged longitudinal sectional view of the section at the discharge end of the furnace.

moved as a unit when necessary, to replace or relocate the upper muffle plates.

A ware or conveyor chamber enclosing the rolls carried on shafts 23 is formed by horizontal upper and lower muffle plates 41 and 42 respectively. These plates may be of heat-resistant alloy such as stainless or Inconel and are supported on ledges formed in the refractory side walls. As shown in Figs. 3A and 5, the upper plates 41 may be supported on ledges 31 and the lower plates on ledges 32. Another series of lower muffle plates 43 may be supported on the lowermost ledges 33 for a purpose to be described. These plates 43 may be of lighter gauge than plates 42 because they carry no load. To meet certain requirements the upper muffle plates 41 may be supported on the upper ledges 30. Fig. 6 shows silicon carbide muffle plates 141 supported on the upper ledges 30. Sectional muffle plates, arranged in the form of an arch may also be used. The steel framework supporting the refractory lining in Fig. 6 would be the same as in Fig. 5, but has not been shown.

Preferably, the upper muffle plates 41 have their central portions suspended on the lower flanged ends of vertical rods 45 extending through the roof block assembly, two such rods being shown for each section. The upper flanged ends of the rods 45 may be yieldingly suspended on spring steel strips 46 adjustably supported at their ends on bolts 47 projecting upwardly from the roof blocks 36. By using the suspending rods 45 a substantially lighter gauge of muffle plate can be used, representing a substantial saving in the high cost of heat-resistant alloy plates. Adjusting the nuts on bolts 47 applies enough tension to the rods 45 to prevent sagging of the muffle plates.

The muffle plates 41, 42 and 43 may have grooves along one edge receiving the edges of adjoining plates to form joints which can be sealed with a suitable refractory cement, by welding overhanging metal strips along the top and bottom edges of the plates. Silicon carbide strips 148 of H cross section can be used to connect silicon carbide muffle plates 141, as shown in Fig. 6, and thus substantially prevent failure of the plates by cracking or breaking in any direction. Additional precaution against failure of such plates may be obtained by suspending the central portions of said plates on silicon carbide rods 145 supported at their upper ends on spring strips 146 carried on bolts 147.

As shown in Figs. 3A and 5 each section 12 has two transverse roll shafts 23 which extend through the roll mounting blocks 28 and 29 in the side walls 27. These shafts are preferably hollow and of heat-resistant alloy. Between the side walls, each shaft has secured thereon end caps 49 (Fig. 2) of heat-resistant alloy, and between the end caps the roll casing may be of heat-resistant alloy for temperatures up to 1900° F. For higher temperatures a silicon carbide casing is used, comprising abutting refractory rings 50 of silicon carbide forming a hollow roll 51. Each ring 50, as shown in Figs. 7 and 8, has an annular core of insulating refractory 52 having a center bore 53 for fitting the shaft 23. Each ring has a concentric groove 54 on one face and a concentric rib 55 on the other face for fitting in the groove 54 of the adjoining ring. Both faces of the rings are provided with V-shaped grooves 56 to match the grooves on adjoining rings and form interconnecting ring joints when filled with insulating cement or the like to lock the rings together.

An air-setting cement weaker than silicon carbide is preferred to minimize cracking along the roll, because if one ring should crack, the weaker cement in the joints would fail before the stress is carried over to adjoining rings, so that a number of rings could crack in misaligned locations without making the roll ineffective. The roll may be made up by placing a shaft on end and laying the successive rings with cement on one end cap, to the desired length, and the other end cap

installed. After curing and drying the roll can be dressed to size. Thus, rolls of varying lengths may be built using multiples of one standard size ring.

These rolls are suitable for relatively high temperatures of the order of 1900° F. to 2400° F. and the silicon carbide rings are extremely abrasion resistant and have a long life when used to convey ceramic slabs and the like. If metal plates, cables or belts are passed over the rolls at somewhat lower temperatures, the silicon carbide rings will cause abrasion of the metal, and this can be avoided by spirally wrapping the rolls with a metal ribbon of heat-resistant alloy, say about 2" wide, thus eliminating the need for replacing the rolls with expensive rolls having casings of heat-resistant alloy such as Inconel.

The end sections 10 and 11 of the furnace are generally similar in construction to intermediate sections 12, except for the addition of a refractory brick wall in one end. Referring to Fig. 3, the exit or discharge end section 10 has the refractory upper end wall 56 extending from the upper muffle plates 41 to the roof blocks 36, and the lower refractory end wall 57 extending from the bottom wall 35 to the upper row of lower muffle plates 42. These end walls 56 and 57 close the end section 25 above and below the conveyor opening in which the rolls 51 are located.

Burner blocks 58, preferably two in number, are built into end wall 56 above the ledge 30, and similar burner blocks 59 are built into end wall 57 between lower muffle plates 42 and 43. Thus, the burner blocks 58 fire into the upper muffle chamber M₁ whether the upper muffle plates 41 are supported on the ledge 31 as shown or on the ledge 30. The burner blocks 59 fire into the lower muffle chamber M₂ formed between the muffle plates 42 and 43. Intake blocks 60 are built into end wall 57 below the muffle plates 43 to introduce hot air or gas into the chamber R formed below the muffle plates 43 for a purpose to be described.

A framework extension is attached to the outer end of discharge section 10, and may comprise vertical angles 13A and horizontal angles 62 supporting a horizontal plate 63 at a level just below that of the muffle plates 42. A conveyor drum 64 has its shaft 65 supported on the angles 62 and the drum extends through an opening in said plate. The drum shaft is operatively connected at one end by a chain 66 to a drive shaft 67 (Fig. 1) which is driven by a suitable motor and gear reducer (not shown).

As shown in Figs. 1 and 3, refractory cooling chamber sections indicated generally at 68 may be connected to the discharge end section 10 when the furnace is used as a kiln. The cooling section adjoining the furnace end section 10 encloses the upper portion of the drum 64 and preferably has one conveyor roll 51A journaled in its side walls. Additional cooling sections having vertical angles 13A may be attached in a manner similar to the manner of connecting the furnace sections 10, 11 and 12.

The conveyor passing over the drum may consist of a number of strands of heat-resistant metal cables 70 in side-by-side relation as shown in the drawings, or one or more wire mesh belts. In using cables, a plurality of pulley grooves may be provided in the drum surface, and cables 70A can be carried on the drum 64 between the cables 70 to extend the conveying surface through the cooling sections 68, as indicated in chain lines in Fig. 3. Where a wire mesh conveyor is used in the furnace, a separately driven conveyor would be required in the cooling sections. The return run of conveyor cables 70 passes under an idler roll 71 on the framework of the end section 10 and is supported on suitable idler rolls 72 on the lower part of the framework of sections 10, 11 and 12.

Referring to Fig. 4 the entrance end section 11 of the furnace has a refractory brick end wall comprising upper

and lower portions 56 and 57 similar to the end wall in discharge section 10 except that the burner blocks are omitted. The upper runs of cables 70 are trained over an idler drum 74 supported on a framework attached to and extending forwardly of the end section 11. This framework includes vertical members 75 connected to vertical angles 13B along section 11 by horizontal channels 76 and top angles 77.

Means for tightening individual cables 70 may consist of a series of pulleys 78, one for each cable, carried on take-up bolts 79 movably mounted on cross bars 80 attached to the vertical frame members 75, and having springs 81 applying tension to said bolts. The return runs of the cables pass through upper and lower thrust rolls 82 and 83 and then to the take-up pulleys 78. From the take-up pulleys the cables are wrapped around a thrust drum 84 and thence go to the idler drum 74.

On the top members 77 of the framework is carried an exhaust fan 85 and its driving motor 86. The intake duct 87 to the fan is connected by suitable ducts 88, extending vertically downward around the sides of furnace section 11, to exhaust ducts 89 and 90 connected into the ends of the muffle chambers M_1 and M_2 (see Figs. 1 and 4). The exhaust ducts serve to exhaust the products of combustion from the muffle chambers as fired by the burners 58 and 59 at the other end of the furnace.

A furnace of variable length, such as shown in Fig. 1, and built up of sections 10, 11 and 12, is adapted for firing enameled aluminum or steel products, for decorating glass or china, and for firing other ceramic products, requiring temperatures from about 900° F. to 1900° F. The close spacing of the muffle plates 41 and 42 provides for efficient heating of the ware by radiation in the low temperature ranges. For firing ware requiring temperatures from about 1900° to 2300° F., the silicon carbide muffle plates 141 supported by silicon carbide suspension rods 145, as shown in Fig. 6, could be used, and refractory slabs 170 carrying the ware could be moved through the furnace on the silicon carbide rolls 51.

If direct firing of the conveyor chamber is desired, this is easily accomplished by removing one or two of the upper muffle plates 41 at both ends of the furnace and blocking off the rest of the upper muffle chamber M_1 . Thus the products of combustion from the burners are forced to travel below the muffle chamber and through the conveyor chamber to the exhaust ducts 89 at the opposite end. The lower muffle chamber need not be used if completely direct firing is desired.

When firing in the low temperatures where heating by radiation is not very efficient, additional thermal efficiency can be obtained by providing convection heating in addition to the radiation heating. This may be accomplished easily by introducing hot air or gas into the lower chamber R below muffle plates 43 through the inlets 60 at the ends of the furnace. The air is forced toward the central part of chamber R where it passes upwardly through the vertical pipes 91 (Figs. 3A and 5) and flows therefrom in opposite directions over and under the conveyor toward the ends of the conveyor chamber. Near the ends of the chamber, the hot air or gas is collected by exhaust ducts 92, preferably in the side walls of the end furnace sections, and returned to the intake blocks 60 by suitable blowers and duct work (not shown) to recirculate it through the furnace. The exhaust ducts 92 are located near to, but not at, the extreme ends of the conveyor chamber so that very little cold air is drawn in while only a small amount of hot air is lost, without requiring doors at the ends of the chamber.

The improved furnace is easily adapted for using controlled atmospheres in the conveyor chamber, by providing gas-tight seals around the roll shafts in the roll mounting blocks, and sliding doors at both ends of the furnace for retaining any desired atmosphere therein. Thus adapted, the furnace would be capable of operating at reducing temperatures of 2200° F. to 2400° F., and

could be used to bright anneal or heat treat metal parts, for example, or to make metal sponge by reducing metals. When using a controlled atmosphere, the hot gases in the conveyor chamber can be recirculated through the chamber R in place of hot air.

The present invention comprises a multi-purpose combination continuous furnace-kiln which is readily adapted for heating and treating a large variety of products over a wide range of temperatures. The overall length is quickly and easily varied by merely changing the number of prefabricated sections. The furnace-kiln is ideally suited, for example, for firing aluminum enamels at 900° F. to 1000° F., for decorating glass or china at 1350° F., or for firing ceramic ware at temperatures up to 1900° F., without changing anything except conveyor speed and temperature. For higher temperatures, the few changes required, such as substituting silicon carbide muffle plates and ware-conveying slabs, are quickly and easily made. The cooling sections 68 at the discharge end are easily added or removed, as required.

What is claimed is:

1. A continuous furnace-kiln comprising a plurality of substantially identical tubular sections detachably joined together in end-to-end relation, the sections at opposite ends having end walls, each of the sections having refractory walls and a steel framework adapted for connection with the framework of an adjoining section, each section having a transverse conveyor roll journaled in opposite walls, upper and lower muffle plates substantially coextensive with each section and supported on said walls above and below said roll forming upper and lower muffle chambers, burners in the end wall of one end section for firing into one end of said muffle chambers, and exhaust means communicating with the opposite ends of said chambers.

2. A continuous furnace-kiln comprising a plurality of substantially identical tubular sections joined together in end-to-end relation, the sections at opposite ends having end walls, each of the sections having refractory walls and a steel framework adapted for connection with the framework of an adjoining section, each section having a transverse conveyor roll journaled in opposite walls, upper and lower muffle plates supported on said walls above and below said roll forming upper and lower muffle chambers, spring suspension means supporting the central portion of each upper muffle plate from the top wall of the section, burners in the end wall of one end section for firing into one end of said muffle chambers, and exhaust means communicating with the opposite ends of said chambers.

3. A continuous furnace-kiln comprising a plurality of substantially identical tubular sections joined together in end-to-end relation, the sections at opposite ends having end walls, each section having refractory side, top and bottom walls lining a steel framework adapted for connection with the framework of an adjoining section, the top wall of each section being separately removable as a unit, a transverse conveyor roll journaled in the side walls of each section, upper and lower muffle plates supported on said side walls above and below said roll and forming upper and lower muffle chambers, burners in the end wall of one section for firing into one end of said muffle chambers, and exhaust means communicating with the opposite ends of said chambers.

4. A continuous furnace-kiln comprising a plurality of substantially identical tubular sections joined together in end-to-end relation, the sections at opposite ends having end walls, each section having refractory side, top and bottom walls lining a steel framework adapted for connection with the framework of an adjoining section, the top wall of each section being separately removable as a unit, a transverse conveyor roll journaled in the side walls of each section, upper and lower muffle plates supported on said side walls above and below said roll and forming upper and lower muffle chambers, spring suspension

means supporting the central portion of each upper muffle plate from the top wall of each section, burners in the end wall of one section for firing into one end of said muffle chambers, and exhaust means communicating with the opposite ends of said chambers.

5. A continuous furnace-kiln comprising a plurality of substantially identical tubular sections detachably joined together in end-to-end relation, each of the sections having refractory walls and a steel framework adapted for connection with the framework of adjoining sections, a transverse conveyor roll journaled in opposite walls, and upper and lower muffle plates supported on said walls and forming muffle chambers above and below said roll, said muffle plates being horizontally coextensive with said section and adapted to have their edges abut the edges of adjoining muffle plates.

6. A continuous furnace-kiln comprising a plurality of substantially identical tubular sections detachably joined together in end-to-end relation, each of the sections having refractory walls and a steel framework adapted for connection with the framework of adjoining sections, a transverse conveyor roll journaled in opposite walls, upper and lower muffle plates supported on said walls and forming muffle chambers above and below said roll, said muffle plates being horizontally coextensive with said section and adapted to have their edges abut the edges of adjoining muffle plates, and spring suspension means supporting the central portion of the upper muffle plate from the top wall of the section.

7. A continuous furnace-kiln comprising a plurality of substantially identical tubular sections detachably joined together in end-to-end relation, each of the sections having refractory walls and a steel framework adapted for connection with the framework of adjoining sections, the top wall of the section being separately removable as a unit, a transverse conveyor roll journaled in opposite walls, and upper and lower muffle plates supported on said walls and forming muffle chambers above and below said roll, said muffle plates being horizontally coextensive with said section and adapted to have their edges abut the edges of adjoining muffle plates.

8. A continuous furnace-kiln comprising a plurality of substantially identical tubular sections joined together in end-to-end relation, each of the sections having refractory walls and a steel framework adapted for connection with the framework of adjoining sections, the top wall of the section being separately removable as a unit, a transverse conveyor roll journaled in opposite walls, upper and lower muffle plates supported on said walls and forming muffle chambers above and below said roll, said muffle plates being horizontally coextensive with said section and adapted to have their edges abut the edges of adjoining muffle plates, and spring suspension means supporting the central portion of the upper muffle plate from the top wall of the section.

9. A continuous furnace-kiln comprising a plurality of substantially identical tubular sections joined together in end-to-end relation, each of the sections having refractory walls and a steel framework adapted for connection with the framework of adjoining sections, a transverse conveyor roll journaled in opposite walls, and upper and lower muffle plates supported on said walls and forming

muffle chambers above and below said roll, each section having a second lower muffle plate spaced below the first and forming a recirculating chamber along the bottom wall of the section, all of said muffle plates being horizontally coextensive with said section and adapted to have their edges abut the edges of adjoining muffle plates, vertical pipes in at least one of the intermediate sections connecting said recirculating chamber with the space between the upper muffle plate and the first lower muffle plate for conducting air from said recirculating chamber into said space.

10. A continuous furnace-kiln comprising a plurality of substantially identical tubular sections joined together in end-to-end relation, the sections at opposite ends having end walls, each of the sections having refractory walls and a steel framework adapted for connection with the framework of an adjoining section, each section having a transverse conveyor roll journaled in opposite walls, upper and lower muffle plates supported on the walls and forming a conveyor roll chamber between upper and lower muffle chambers, a second lower muffle plate spaced below the first and forming a recirculating chamber above the bottom wall of the section, a vertical pipe in at least one of the intermediate sections connecting said recirculating chamber with said conveyor roll chamber, air intake means in the end walls of said end sections communicating with said recirculating chamber, and air exhaust means in the side walls of said end sections communicating with said conveyor roll chamber.

11. The method of recirculating heated air through a continuous furnace having a conveyor chamber extending longitudinally therethrough and a muffle chamber parallel with said conveyor chamber, comprising withdrawing heated air from said conveyor chamber adjacent to its ends, forcing said air through the ends of said furnace along the outer side of said muffle chamber, and conducting said air through the central portion of said muffle chamber to the central portion of said conveyor chamber.

12. The method of recirculating heated air through a continuous furnace having a conveyor chamber extending longitudinally therethrough and a muffle chamber parallel with said conveyor chamber, comprising withdrawing heated air from said conveyor chamber adjacent to its ends, forcing said air through the ends of said furnace along the outer side of said muffle chamber, and conducting said air to the central portion of said conveyor chamber.
